ANTIRATTLE DEVICE FOR WINDOWS

Albert T. Potter, Detroit, Mich., assignor to Ainsworth Manufacturing Corporation, a corporation of Michigan

Application December 11, 1933, Serial No. 701,748

5 Claims. (Cl. 296—48)

This invention relates to windows in motor vehicles and it has particular relation to an arrangement for slidably mounting the window so as to prevent rattling.

5 One object of the invention is to provide an improved window mounting which will constantly operate to eliminate rattles such as frequently are apparent, particularly after the motor vehicle has been in use for some time.

10 Another object of the invention is to provide an improved window mounting wherein means will be provided for preventing loose and rattling movement of the window in its own plane as well as transversely to such plane.

15 Another object of the invention is to provide an improved window mounting which efficiently uses resiliently pressed rollers for avoiding rattling between the window and the guideways reciprocally guiding it in its movement.

20 Other objects of the invention will become apparent from the following description taken in conjunction with the drawings and from the claims hereinafter set forth.

25 For a better understanding of the invention reference may be had to the accompanying drawings forming a part of the specification, wherein:

Figure 1 is a fragmentary view of a motor vehicle illustrating the manner in which a window is mounted according to one form of the invention.

30 Fig. 2 is a fragmentary view on a larger scale with certain parts shown in cross section, of one side of the window mounting.

Fig. 3 is a cross-sectional view taken substantially along the line 3—3 of Fig. 2.

Fig. 4 is a cross-sectional view on a larger scale taken substantially along the line 4—4 of Fig. 2.

Fig. 5 is a view similar to Fig. 2, but illustrating a different form of the invention.

40 Fig. 6 is a cross-sectional view taken substantially along the line 6—6 of Fig. 5.

Fig. 7 is a cross-sectional view on a larger scale taken substantially along line 7—7 of Fig. 5.

Referring to Fig. 1, the window is indicated at 10, and a metal channel receiving the lower edge of the window is indicated at 11. For reciprocating the window, slides 12 may be provided on the channel 11, which are operatively connected by links 13 to a gear mechanism 14 that in turn is actuated by a handle 15. Operating mechanism of this character is not a part of this invention per se.

The vehicle body at opposed edges of the window is provided with channel guideways 16 shown best by Fig. 4, and these guideways respectively receive auxiliary channel members 18 that are somewhat smaller in size than the guideways 16 and which receive side edges of the window. For sealing the space between the channel members 18 against ingress of water or the like, resilient seal-

ing strips 20 may be provided in small channel portions 21 formed in the free edge portions of the legs or side walls of the guideways 16 and such sealing strips engage opposed legs of the channel members 18, respectively. The channel members 18 project below the window and for connecting them to the channel member 11, metal bracket members 23 are interposed between opposite ends of the latter and the channel members 18 and such bracket members may be welded 5 as indicated at 24 to the ends of the channel member 11. The bracket members include laterally directed lip portions 25 and 26 that project into the channel members 18 and which are secured thereto by means of screws 28 and 29 respectively. Thus, the window is supported on a frame comprising the channel member 11 receiving its lower edge and the two side channel members 18 that are reciprocatory in the guideways 16. 10

For preventing rattling between the auxiliary channel members 18 and the guideways 16, in the plane of the window and transversely between the guideways, bell cranks 30 are pivotally mounted on the lower screws 29 as best shown by Fig. 3, 15 and each of these bell cranks comprises similar spaced elements 31 and 32 of bell crank character, between which at one end of the bell crank a roller 33 is journaled. Intermediate their ends the bell crank elements 31 and 32 are journaled 20 on a nut 34 into which the screw 29 is threaded and their opposite ends are connected to a tensioned spring 35 that in turn is connected to a lip 36 on the bracket 23. Adjacent the roller 33, the base portion of the auxiliary channel member 30 30 is recessed as indicated at 37 in Fig. 2, so as to permit the roller to project into rolling contact with the base portion of the guideway 16. Thus, at opposite edges of the window, the rollers 33 are resiliently pressed against the base portions of the guideways 16 at all times so that rattling of the window transversely between the opposed guideways 16 is prevented.

For preventing rattling of the window transversely to its plane, a U-shaped bracket 40, best 45 shown in Fig. 2 at 40, is secured by screws 41 to the base portion of the auxiliary channel members 18 and between the base portion of this U-shaped member and the base portion of the auxiliary channel member, spaced plates 42 and 43 are provided which are pivotally mounted on a pin projecting between the base portion of the U-shaped member and the base portion of the auxiliary channel members. It may be added that a strengthening strip 46 may be disposed 50 between the bracket 40 and the base portion of the auxiliary channel member 18. Between the plates 42 and 43 and also journaled on the pin 44, a roller 48 is provided and as best shown by Fig. 3, this roller projects through an opening 50 formed 55 60

in one leg of the channel 18 and so that it may have rolling contact with the adjacent leg of the guideway 16. The plates 42 and 43 also have a second roller 51 journaled on a pin 52 connecting the plates and this roller is adapted to project through an opening 53 in the opposite leg of the channel 18 so as to engage the opposite leg of the guideway 16. The plates 42 and 43 preferably comprise part of a bifurcated bracket connected by a web 54 as shown by Fig. 3, and a lip 55 projects from the plate and has a pin portion 56 secured thereto which receives a spring 57 that engages one leg of the channel 18. This spring constantly urges the plates 42 and 43 about the pin 44, thereby maintaining both rollers 48 and 51 constantly in rolling contact with opposed legs of the guideway channel 16. The same construction, although inverted, is provided at a lower point as clearly shown by Fig. 3.

Referring now to Figs. 5, 6 and particularly to Fig. 7, the guideway 16 has its legs projecting beyond the sealing strips 20 to form guide portions 60 and 61 that terminate in outwardly directed flanges 62. The bracket member 23 in this case extends into the auxiliary channel 18 and is secured thereto by bolts 63, and outwardly of the channel is provided with vertically spaced pressed in channel portions 64 having a base 65 and side walls 66. Within each of the channel portions, although disposed in relatively inverted positions, a roller supporting member 67 is disposed, which comprises spaced plate portions 68 and 69 connected at one end by an integral web 70 and at the other end of a curved socket portion 71. A roller 72 is journaled on a pin 73 connecting the plate portions, and a second roller 74 is journaled on a pin 75 extending through the plate portions and also the side walls 66 of the bracket member 23. From this it will be seen that the member 67 may pivot about pin 75. The roller 72 is resiliently pressed against the guide portion 61 of the channel 16, by means of a spring 77 seated in the socket portion 71 and which abuts the base portion 65 of the channel portion 64 while roller 74 partially projects through a slot 78 in the base portion 65 and engages the guide portion 60 of the channel. It follows that the rollers will resiliently be pressed against the guide portions 60 and 61 by using the spring 77 and pivotal action of the holding member 67.

One of the bell crank arms 30 is pivotally mounted on that portion of the bracket 23 projecting into the channel 18 and it will be recalled that this bell crank has a roller 33 extending through a slot 37 in the base of this channel and which is resiliently pressed against the base of channel 16.

The arrangement of rollers described is provided at both sides of the window and it is apparent then that certain of the resiliently pressed rollers will prevent rattling and loose movement of the window in its own plane and that others will prevent rattling or loose movement of the window transversely to its plane.

The invention provides a simple and efficient form of window and anti-rattling arrangement to avoid rattling constantly throughout the life of the motor vehicle. It is furthermore apparent that the rollers will not strongly resist movement of the window owing to the fact that they have

rolling contact with the stationary channel guideway 16. The invention insures a smoothly and quietly working window and one which will avoid rattling which is so common in motor vehicles at the present time.

Although only two forms of the invention have been described and illustrated in detail, it will be apparent to those skilled in the art that various modifications may be made without departing from the scope of the appended claims.

I claim:

1. In combination with a vehicle body having a channel guideway member for a window, an auxiliary channel member disposed in and movable lengthwise of the first member, a window, a member supporting the window and secured to the auxiliary channel for movement therewith, rollers mounted on the supporting member and disposed entirely outside of the auxiliary channel for engagement with free edge portions of the legs of the guideway member, and means resiliently holding the rollers in engagement with said portions of the guideway member.

2. In combination with a vehicle body having a channel guide member for a window, an auxiliary channel member disposed in and movable lengthwise of the first member, the legs of the guide member projecting beyond the legs of the auxiliary member, resiliently pressed rollers operatively carried by the auxiliary member and engaging the projecting portions of the legs on the guide member, and sealing means between the legs of the auxiliary member and the legs of the guide member.

3. In combination with a vehicle body having a channel guide member for a window, an auxiliary channel member disposed in and movable lengthwise of the first member, the legs of the guide member projecting beyond the legs of the auxiliary member, resiliently pressed rollers operatively carried by the auxiliary member and engaging the projecting portions of the legs on the guide member, channel portions in the legs of the guide member and sealing means in such channel and engaging the legs of the auxiliary member.

4. In combination with a vehicle body having channel guideway members for a window, auxiliary channel members disposed in and movable lengthwise of the first members, a window, means mounting the window on said auxiliary channel members, rollers operatively mounted on the auxiliary channels and disposed outwardly of and adjacent the free edges of the legs thereof, and engaging the inner faces of the legs of the guideway members adjacent the edges thereof, and means resiliently holding the rollers against said inner faces of the guideway members.

5. In combination with a vehicle body having a channel guide member for a window, a window, a channel member receiving the lower edge of the window glass, an auxiliary channel member disposed in and movable lengthwise of the guide member and projecting below the glass receiving channel member, a bracket member extending between the glass receiving channel and the projecting portion of the auxiliary channel and being rigidly connected to both the channel members, and resiliently pressed rollers mounted on the bracket member and engaging the legs of the guide member.

ALBERT T. POTTER.
